UNITED STATES PATENT OFFICE

LAWRENCE E. GOELLER, OF CIRCLEVILLE, OHIO, ASSIGNOR TO THE M. G. GOELLER'S SONS CO., OF CIRCLEVILLE, OHIO, A CORPORATION OF OHIO

BROOM

Application filed January 8, 1931. Serial No. 507,495.

This invention relates to brooms, brushes and the like, and it has for its general object the provision of a novel construction of broom head and receiving socket therefor for securing the broom to the broom handle.

One of the more specific objects of the invention is to provide a metal bound broom head comprising an encircling band within which the fibers of the broom are pressed and secured under pressure.

Another object of the invention is the provision of a stamped metal socket having reinforcing ribs formed thereupon, vertically, horizontally and diagonally whereby distortion of the socket through excessive use or abuse, is prevented.

A further object of the invention is the provision of a socket in which the said ribs are stamped, some on one side and some on the other, whereby the effective thickness of the sheet stock from which the socket is made is multiplied and its strength thereby increased.

Still another object of the invention is the provision of dual utility for the ribs, the vertical ribs forming a channel for receiving the broom handle, the horizontal ribs forming a reinforcement for the free edges of the socket which adjoin the flexible portion of the head, and the diagonal ribs pressing inwardly against the broom head for frictionally holding it in place within the socket.

Other objects of the invention will appear as the following description of a preferred and practical embodiment thereof proceeds.

In the drawing in which the same characters of reference are used throughout the several figures to designate identical parts:

Figure 1 is a front elevation of a broom embracing the features of the present invention, a part of the handle being omitted;

Figure 2 is an end elevation;

Figure 3 is a vertical cross section taken along the line 3—3 of Figure 1; and

Figure 4 is a vertical section taken along the line 4—4 of Figure 3.

Referring now in detail to the several figures, the numeral 1 represents the broom head proper, which is composed of a sweeping sheaf of straws or fibers, bound together

with thread in the usual manner indicated at 2 and sewn through and through as usual to segregate the straws or fibers into a plurality of wisps or tufts. The upper end of the broom head is bound with a metallic band 3 and the fibers are brought together under great pressure within this band and secured through and through by nails 4 or similar devices, the free ends of which are clinched or otherwise secured, on the opposite side of the broom head, so as to retain the straws or fibers constituting the upper end of the broom head into a solid and compact manner.

The broom head thus formed is secured in a socket 5 consisting of complementary dished halves 6 and 7 suitably secured together at their meeting edges 8. The socket thus formed has a cylindrical neck 9 for receiving the broom handle 10 and the opposite end of the socket presents an enlarged long and relatively narrow opening 11 in which the broom head is inserted. The broom head is preferably somewhat tapered towards its upper end and the socket 5 is similarly tapered so that when the broom head is pushed into the socket it assumes a wedged position within said socket.

The socket 5 is provided on its opposite faces with ribs stamped or otherwise suitably formed, one pair of oppositely facing ribs 12 being stamped outwardly providing aligned channels on the inner side of the socket member adjacent the neck for receiving the broom handle and holding it against lateral displacement.

The free edge of the socket surrounding the opening 11 is flared outwardly so that the sharp edges of the socket 5 will not cut the fibers when the head of the broom flexes, in use. A transverse rib 15 is stamped outwardly in the socket member on each side extending parallel to this flared edge and adjacent thereto, and constitutes a reinforcement which prevents deforming of the ends through the pressure of the flexing broom.

The vertical and transverse ribs thus described also act as reinforcing members for the socket, the vertical ribs preventing the socket from collapsing or bending along a

horizontal fold adjacent the neck while the transverse ribs maintain the enlarged relatively flat part of the socket against bending.

Between these two sets of ribs are diagonal 5 ribs 13 stamped in the opposite sides of the socket member and extending inwardly. Due to their diagonal relation, these ribs act as the diagonal struts in any parallelogram structure and prevent distortion of the socket 10 through excessive use or abuse.

The fact that certain of the ribs are stamped outwardly while others are stamped inwardly, has the effect of increasing the thickness of the metal stock of which the socket 15 is made several times and thus proportionately increases the strength of the construction.

It will be noted that the inwardly stamped diagonal ribs 13 on each side of the socket converge downwardly toward the median line 20 of the socket forming with the intervening spaces a diagonal corrugation which grips the upper banded end of the broom head to prevent the latter loosening or coming out of the socket member.

25 In the manufacture of the broom rivets 14 pass through both sides of the socket member and through the banded portion of the broom head, said rivets being inserted in the recesses of the diagonal ribs and pressing the latter 30 intimately into the metal band of the broom head. It is obvious therefore, that the pressure of the rivets causes the band to assume a somewhat, even though slight, undulating form, interfitting within the spaces between 35 the diagonal ribs so that any force tending to dislodge the broom head tends to tighten these interfitting spaces, wedgelike against said ribs and thereby prevents loosening of the broom head relative to the socket.

40 The positioning of the rivets within the hollows formed by the diagonal ribs places the heads and tails of the rivets below the general plane of the socket surfaces so that they will not deface furniture against which the sides 45 of the broom sockets may come into contact.

A broom constructed according to the principles of the invention as above described provides a head which securely holds the straws or fibers and protects same from being 50 chafed or cut, due to the outwardly flaring edges of the broom socket. Moreover, the broom head itself is wedged in the socket in one direction by the corresponding tapered 55 shapes of both the broom head and the socket, while the diagonal strut ribs have the effect as above set forth of defining wedge-like areas of contact between the socket and the banded portion of the broom head which 60 prevents the working loose of the broom head from the socket in the opposite direction.

The broom handle may be riveted or otherwise suitably secured within the socket.

65 While I have in the above description defined a preferred and practical form of the

invention, it is to be understood that variations in the construction of the same and in the arrangement of the parts may be made without transcending the scope of the invention as claimed.

70 What I claim is:

1. A broom construction comprising a socket member and broom head, the latter including a sweeping-sheaf and a metallic band compressively encompassing the sweeping-sheaf at one end, said broom head at the banded end and said socket being correspondingly tapered and assembled in telescoped relation, the sides of said socket being provided with inwardly projecting inclined ribs and means passing through said ribs and bands and for maintaining said ribs clampably pressed against said band.

75 2. A broom construction comprising a socket member and broom head, the latter including a sweeping-sheaf and a metallic band compressively encompassing the sweeping-sheaf at one end, said broom head at the banded end and said socket being correspondingly tapered and assembled in telescoped relation, the sides of said socket being formed with inwardly projecting inclined ribs converging toward the median portions of said sides in the direction of the broom head, said ribs being clampably pressed against said band.

80 3. A broom construction as claimed in claim 2, including means passing through said ribs and socket for maintaining said ribs in clamped relation against said broom head.

85 4. A broom construction comprising a socket member and broom head, the latter including a sweeping-sheaf and a metallic band compressively encompassing the sweeping-sheaf at one end, said broom head at the banded end and said socket being correspondingly tapered and assembled in telescoped relation, the sides of said socket being formed with inwardly stamped inclined ribs and means passing through the sides of the socket in the depressions formed by said ribs, and through said band, for maintaining said ribs clampably pressed against said band.

90 5. A broom construction as claimed in claim 4, the ribs converging toward the median portions of said sides in the direction of the broom head.

95 6. A broom construction comprising a socket member adapted to receive a broom head, said socket member being formed on its opposite sides with outwardly stamped corresponding ribs forming a channel for the broom handle, transverse outwardly stamped ribs adjacent the edges of said socket remote from said broom handle, and diagonal inwardly stamped ribs located in a zone above said transverse ribs.

100 In testimony whereof I affix my signature.
